DESIGN FOR A DISPLAY SIGN

Ernest D. Maloy, Cedar Rapids, Iowa, assignor to
Mack Manufacturing Corporation, a corpora-
tion of Iowa

Application January 9, 1941, Serial No. 97,910

Term of patent 7 years

To all whom it may concern:

Be it known that I, Ernest D. Maloy, a citizen of the United States, residing at Cedar Rapids, in the county of Linn and State of Iowa, have invented a new, original, and ornamental Design for Display Signs, of which the following is a specification, reference being had to the accompanying drawing, forming part thereof.

Figure 1 is a plan view of the display sign showing my new design.

Figure 2 is a view in side elevation of the display sign shown in Figure 1.

Figure 3 is a view in front elevation of the display sign shown in Figures 1 and 2, with a portion of the glass cover broken away, and

Figure 4 is a view in section taken along the line 4—4 of Figure 2 to illustrate the position of the tubing and the panels back of the tubing.

I claim:

The ornamental design for a display sign, as shown.

ERNEST D. MALOY.
